UNITED STATES PATENT OFFICE

RUDOLPH FRANK STEHLIK, OF CHICAGO, ILLINOIS, ASSIGNOR TO RESERVE HOLDING COMPANY, OF KANSAS CITY, MISSOURI, A CORPORATION OF DELAWARE

MULTIOFFICE TELEPHONE SYSTEM

Application filed April 22, 1927, Serial No. 185,696. Renewed July 16, 1930.

This invention relates in general to multi-office telephone systems but more particularly to such systems as comprise in one network offices or exchanges of two different kinds, the offices of one kind being manual offices wherein connections are completed by operators, while the other kind of offices are automatic offices in which connections are completed by means of automatic switches, and the object of the invention is to provide new and improved circuit arrangements for handling inter-office calls between the automatic and manual exchanges.

Systems having both kinds of exchanges as above pointed out are becoming quite common and may arise either by consolidation of existing manual and automatic systems, serving the same territory, or by the process of changing over a manual system to an automatic system. Usually in the latter case only one office at a time is converted from manual to automatic and it follows that during the period of transition there will necessarily be both kinds of offices in operation. However the above situation may arise, it is necessary to provide suitable circuit arrangements for handling calls from the manual offices to the automatic offices, and from the automatic offices to the manual offices. The present invention is concerned only with the latter class of calls, and provides certain improvements in a system comprising automatic to manual trunks which are accessible to selector switches in the automatic offices and terminate in plugs in front of a B operator at the manual office, together with call registers for registering the digits in telephone numbers called by automatic subscribers when the trunks are taken into use, and an indicating device upon which such numbers are shown to the operator one after the other as fast as she can complete the desired connections.

In known systems of this type a small group of call register sets are usually provided to serve a comparatively large group of trunk lines and so called register selectors are used for associating trunk lines with idle register sets. With this arrangement it is necessary for the register selector associated with the trunk line in use to select an idle

register set before the second digit of the called number is dialled, otherwise trouble occurs. If the second digit of a telephone number is dialled before the register selector has selected an idle register set it will result in a "mutilated call" or a "wrong number", depending on whether the second digit is entirely lost or not. A "mutilated call" is a call in which the complete second digit of the called number is lost. The remaining digits of the called number are registered on the registers and are subsequently displayed to the operator after a certain time interval if the register selector has in the meantime selected an idle register set. In such cases only a portion of a complete number is displayed, and the B operator connects the calling party to the trouble operator who either completes the call or advises the calling subscriber to hang up and call again. A call will result in a "wrong number" if a portion of the impulses of the second digit is lost while the remaining impulses of the second digit are recorded on the register set which has just been seized by the register selector. In this case a complete number will be displayed, and the operator has no way of telling that such number was not correctly registered and therefore when the operator plugs in on the line of the number displayed a connection to a wrong subscriber's line is completed. From the foregoing it will plainly be seen that both "mutilated calls" and "wrong number" calls occur as a result of the second digit being dialled during the time the register selector is hunting for an idle register set.

The main object of the invention is to provide a new and improved system of the general character described, in which the troubles pointed out cannot occur. This is accomplished by providing a register individual to each cord circuit for recording the number of impulses in each digit and for then transferring the registered digit after each series of impulses to an idle register set which has by this time been seized by the register selector. By this arrangement the second digit can be dialled as soon as the trunk is seized, and while the register selector is hunting for an idle register set, so that the occurrence of

"mutilated calls" and "wrong number" calls, resulting as above set forth, is made impossible.

Various other features will be pointed out in the detailed specification which follows.

In the drawings, comprising Figs. 1, 2, 3, and 4, there are shown by means of the usual circuit diagrams the apparatus and circuit connections thereof which are involved in a complete connection extending from the automatic substation A, Fig. 1, to a manual substation A', Fig. 2. The apparatus indicated in Fig. 1 is located in an automatic exchange, while the apparatus indicated in Figs. 2, 3, and 4 is located in a manual exchange. Inasmuch as the automatic switching equipment itself and the manual equipment are both well known and of the usual type, no detailed description of the mechanical features of this apparatus will be given, except in so far as it is found convenient or necessary to do so in the explanation of the operation of the circuits.

Referring to Fig. 1, the substation A is one of a plurality of ordinary automatic substations terminating in the automatic exchange previously referred to, and is provided with the usual talking equipment and ringer, and also with a calling device of well known type which is indicated by the reference character S, through the medium of which the subscriber controls the central office switches.

The line conductors 11 and 12 extend to the exchange where they terminate in the line switch C, which may be briefly described as a rotary line switch whose movable terminals or wipers have no normal position, and which have movement in a forward direction only. The construction of a line switch of this type is well known in the art, and its function, also well understood, is to extend its associated line when calling to an idle trunk line. In carrying out this object, a plurality of these individual line switches are given access to a group of trunk lines extending to first selector switches. One of the trunk lines to which the line switch C has access is shown in the drawing as extending to the first selector D, which is a vertical and rotary selector of the well known Strowger type. In a multi-office system of the kind herein contemplated the first selector switches are usually known as office selectors and the selector D in common with a plurality of similar selectors has access to a plurality of groups of trunk lines, each of which groups may extend to a different office or exchange in the system. Some of these groups of trunk lines may extend to automatic exchanges, while other groups may extend to manual exchanges.

A trunk line in one of the latter groups is shown in the drawing, and comprises the repeater E and the trunk line conductors 130 and 131, which extend to the manual ex-

change in question and there terminate in the plug ending cord circuit O, Fig. 2. The cord circuit O is one of a plurality of similar cord circuits at a B operator's position in the manual exchange and constitutes the means whereby the trunk line shown may be connected by the operator with any one of the manual lines terminating in the manual exchange. One of these lines is the line of substation A', which with its associated line equipment is shown at the right of Fig. 2.

The repeater E is an automatic impulse repeater of the general type in common use, and in addition to repeating operating impulses to the distant manual exchange, provides holding circuits for the automatic switches, and thus renders it unnecessary to use more than two conductors for the inter-office trunk line.

From the foregoing it will be understood that the operation of an office selector, such as the selector D, in response to the calling of the first digit in the telephone number of a line in the manual exchange, will result in extending the connection from the line of the calling automatic subscriber to an idle plug ending cord circuit in the manual exchange. In order to take care of the remaining digits in the numbers there is provided for each B operator's position a plurality of register sets as hereinbefore stated, each set being capable of registering all the digits in a telephone number, with the exception, of course, of the first digit which controls the office selector in the automatic exchange. In addition, each cord circuit is provided with a common registering device, or relay group, which is capable of receiving a series of digits and of transferring them to the registers of a selected register set. Each cord circuit is of course also provided with a register selector which may be engaged in hunting for a register set during the time in which a digit is being received.

In Fig. 3 I have shown a relay group RG and a register selector C', both of which are individual to the cord circuit O. In Fig. 4 I have shown one of the register sets accessible to the register selector C', and also a consecution control switch CCS for displaying registered numbers one at a time.

The relay group RG, Fig. 3, comprises a plurality of relays for recording the number of impulses in each digit and for transferring the digit after each series of impulses to one of the relay groups in the seized register set. The register selector C', Fig. 3, is a rotary type line switch which is individual to the cord circuit O, Fig. 2, and which has access to the register set shown in the drawing, and also to the other register sets which are provided at this particular B operator's position in which the cord circuit O terminates. Line switch C' is of well known construction and function and on this account

will not be described in detail as to its mechanical operation.

The register set, Fig. 4, comprises the relay group registers R' , R^2 , R^3 and R^4 . The relay group registers R^2 , R^3 , and R^4 are identical to the relay group R' and, therefore, only the relays 500 and 505, 600 and 605, and 700 and 705, corresponding to the relays 400 and 405, have been shown. It will be understood that each relay group register has relays connected thereto in the same manner that relays such as relays 401, 402, 403 and 404 are connected to relay group register R' . In Fig. 3 I have shown a chart showing the energized condition of the relays of the relay group RG after each of the ten impulses and in Fig. 4 another chart shows the energized condition of the storage relays of the register R' after the relay group transfers the digits to such storage relays.

The register sets, as previously explained, comprise relay groups, there being a group for each digit in the called number, except, of course, the first digit. The arrangement is such that the various digit lamps are connected up by the operation of one or more relays of a group. A transfer relay of each group is operated to prepare the next group and so on. When a final digit has been set up the transfer relay of the last group closes a circuit to cause a consecution control switch to select the register set which is in use after which a circuit is closed to light the call indicating lamps corresponding to the digits set up.

The indicating device by means of which called telephone numbers are shown to the operator is shown in connection with the registers shown in Fig. 4. It comprises, essentially, a plurality of groups of switchboard lamps, there being one group of lamps for each register relay group in a register set. Only one group of lamps, however, have been shown. It will be understood that the lamps have the function of illuminating the digits of the called numbers and causing them to stand out so as to be readily distinguished. The digits are preferably marked in black on the reverse side of a white semi-transparent surface and ordinarily are not very conspicuous. But when the switchboard lamp immediately behind any character or figure is lighted such character or figure will stand out very clearly and is read with great facility. The lamps of the indicating device are wired to contacts on the relays of the register shown, and are also wired to similar contacts on the relays of the other registers at the position.

As stated hereinbefore, there are a plurality of register sets providing for the registration of a plurality of calls simultaneously or close together. These registered calls are displayed on the indicating device one after the other as fast as the operator can complete the connection by plugging into the multiple

jacks which correspond to the numbers displayed. In order to switch the calls over onto the indicating device in succession a so-called consecution control switch is provided. This switch is shown in Fig. 4 where it is indicated by reference character CCS, and comprises a single wiper and bank of contacts as shown in the drawing. The switch CCS is mechanically the same in construction as the rotary line switch C, Fig. 1, that is, its wipers have no normal position and move in a forward direction only. The circuits, however, are changed and will be described hereinafter.

Having described in a general way the layout of the system herein disclosed, the operation of the circuits will now be described more in detail, it being assumed for this purpose that the subscriber at substation A, Fig. 1, desires to obtain a connection with the manual subscriber at substation A', Fig. 2, whose telephone number, it will be assumed is 23456. When the receiver is removed at substation A, a circuit is completed over the line conductors 11 and 12 for the line relay 14 of the individual line switch C. Upon energizing, the line relay completes at its armature 20 a circuit which extends through the switching relay 13 and the stepping magnet 15 in series to battery, and at its armature 19 connects the test wiper 26 to the above circuit at a point midway between the switching relay and the said stepping magnet. The operation now depends upon whether the first selector trunk with which the wipers of the line switch are in connection is busy or is not busy. If this trunk line is busy the test contact 31 associated therewith will have a ground potential upon it, the switching relay 13 will be short circuited, and the stepping magnet 15, which interrupts its own circuit, will operate as a buzzer to advance the wipers 25-27, inclusive, step by step in search of an idle trunk line. This operation will continue as long as the test wiper 26 continues to engage grounded or busy contacts. However, we may assume that in the present case when the call is initiated the selector D is idle, and the test contact 31 therefore is not grounded. Under these circumstances when the line relay 14 is energized the switching relay 13 is energized immediately afterwards, with the result that the line conductors 11 and 12 are disconnected from the winding of the line relay 14 and from ground, respectively, and are extended by way of armatures 16 and 18 and their working contacts, wipers 25 and 27, bank contacts 30 and 32, and armatures 60 and 62 and their resting contacts, to the upper and lower windings of the line relay 50 of the selector D.

As soon as the line is extended to the selector D as above described, the line relay 50 will be energized and will close the circuit of

the slow acting release relay 51. Upon energizing, the latter relay prepares the circuits of the selector for operation in its vertical movement in the usual manner, and also completes a holding circuit extending back to the line switch C as follows: ground, working contact of armature 63 and the said armature, conductor 64, bank contact 31, test wiper 26, armature 17 and its working contact, winding of the switching relay 13, and the winding of the stepping magnet 15 to battery. It is understood that the above holding circuit is completed before the slow acting relay 14 has had time to deenergize. In addition to maintaining the switching relay energized, the holding circuit also serves to provide ground to the multiples of test contact 31 and also to the multiple test contacts in which the private normal conductor 28 terminates in the banks of the connectors which have access to the line of substation A, thereby guarding the connection against intrusion in the customary manner.

The calling subscriber may now operate his calling device S in accordance with the first digit of the desired number. Two interruptions are thereby produced in the circuit of the line relay 50, and the said relay is accordingly twice deenergized momentarily, transmitting at each deenergization an impulse of current through the slow acting series relay 52 and the vertical magnet 56 to battery. By the operation of the vertical magnet the selector shaft is raised two steps, whereupon the wipers 70-72, inclusive, will be standing opposite the level of bank contacts in which are terminated the trunk lines extending to the manual exchange. The slow acting relay 52 is energized in series with the vertical magnet, retaining the armature attracted throughout the vertical movement of the switch, and upon the closure of the vertical off normal springs 59 completes a circuit for the stepping relay 53. Upon energizing, relay 53 prepares a circuit for the rotary magnet 54 at its lower armature and at its upper armature establishes a locking circuit for itself. At the end of the vertical movement of the switch the slow acting relay 52 is deenergized and closes the circuit of the rotary magnet, which is thereupon energized to advance the wipers 70-72, inclusive, into engagement with the first set of bank contacts in the level opposite which they were raised. The rotary magnet 54 also breaks the locking circuit of the stepping relay 53 which accordingly deenergizes and breaks the circuit of the rotary magnet, which thereupon deenergizes also and again closes its interrupter contact.

The operation now depends upon whether the trunk line with which the wipers have connected is busy or is not busy. If this trunk line is busy the test contact associated therewith will be grounded and the stepping re-

lay 53 will be energized over a circuit which extends by way of the test wiper 71, armature 61 and its resting contact, off-normal springs 59, interrupter contact of the rotary magnet, and the winding of the stepping relay 53 to battery. The stepping relay will therefore again close the circuit of the rotary magnet 54, which will operate to rotate the switch wipers into engagement with the next set of bank contacts. This operation in which the stepping relay and the rotary magnet are alternately energized and deenergized will continue as long as the test wiper 71 continues to engage grounded or busy test contacts. In the present case it will be assumed that the trunk shown in the drawings is the first idle trunk line, and when therefore the test wiper 71 arrives at test contact 74 and the rotary magnet is deenergized, the stepping relay 53 will not again be operated, but instead the switching relay 55, which heretofore has been short-circuited, will be energized by current flowing over the following path: Grounded conductor 64, winding of the switching relay 55, off-normal springs 59, interrupter contact of the rotary magnet 54, and the winding of the stepping relay 53 to battery. Owing to the high resistance of the switching relay 55, stepping relay 53 is not operated. Upon energizing, relay 55 disconnects the incoming line conductors from the windings of the line relay 50 and extends them by way of armatures 60 and 62 and their working contacts, wipers 70 and 72, bank contacts 73 and 75, trunk conductors 76 and 78, and normally closed contacts of the reversing relay 100 to the upper and lower windings of the line relay 101 of the repeater E. When the line is extended to the repeater as above explained the line relay 101 is energized and closes the circuit of the slow acting release relay 102. Upon energizing, relay 102 completes a holding circuit extending back to the selector D and line switch C as follows: ground, armature 112 and its working contact, conductor 77, test contact 74, test wiper 71, and the armature 61 and its working contact to conductor 64, where it joins the previously described holding circuit extending back to the line switch C. The above described circuit serves to maintain relays 55 and 13 energized throughout the duration of the connection.

In addition to closing the holding circuit for the automatic switches C and D, the relay 102 of the repeater E prepares a circuit at its armature 115 for the slow acting relay 103, closes a circuit at its armature 114 which causes the energization of slow-to-energize relay 104, and at its armature 113 completes a circuit for energizing line relay 202 of the cord circuit over the following path: from ground by way of normally closed springs controlled by armature 118 of slow-to-energize relay 104, working contact of armature 130

113 and said armature, conductor 130, upper left hand winding of the repeating coil, Fig. 2, normally closed springs controlled by armature 214, and upper winding of line relay 202 to battery. The line relay, upon energizing, completes a circuit at armature 218 for energizing slow to release relay 203 and the latter relay at armatures 222 connects ground to the lower winding of the line relay. By this time, slow-to-energize relay 104 in the repeater E is completely energized and said relay at armature 120 and its working contact connects ground to release trunk conductor 77 for a purpose which will be explained hereinafter; and at armature 118, relay 104 removes the ground from conductor 130 and substitutes a bridge across the trunk conductors 130 and 131 for maintaining the line relay 202 of the cord circuit O in energized position. The bridge for maintaining line relay 202 energized may be traced as follows: from ground by way of armature 222 and its working contact, lower winding of line relay 202, normally closed springs controlled by armature 215, lower left hand winding of the repeating coil, conductor 131, armature 111 and its working contact, right hand winding of the impedance coil 106, normally closed springs controlled by armature 108, lower winding of polarized relay 105, resting contact of armature 116 and said armature, armature 118 and its working contact, and thence over the previously traced circuit to the upper winding of the line relay 202 to battery. Relay 104 at armature 121, also closed a circuit for the upper polarizing winding of relay 105. Polarized relay 105, however, does not now energize because the current flow through its lower winding is in the wrong direction.

When the calling line is extended to the line relay 202 as above explained, said relay energizes and at armatures 216 and 217 opens the circuit of the impulsing conductors 260 and 261, and at armature 218 completes a circuit for energizing relay 203 as previously explained. Relay 203, upon energizing, prepares the impulsing circuit to impulsing conductors 260 and 261 at armatures 219 and 220, at armature 222 and its working contact connects ground to the lower winding of the line relay 202, and at armature 224 and its working contact prepares a circuit for relay 201.

In addition to the foregoing, relay 203 at its armatures 221 and 223 prepares the operating and testing circuits for the register selector switch C' shown in Fig. 3. A circuit now extends to the switching relay 204 and the stepping magnet 350 in series as follows: from ground at armature 224 and its working contact, armature 235 and its resting contact, armature 241 and its resting contact, winding of switching relay 204, armature 233 and its resting contact, resting contact of armature 240 and said armature, conductor 266, interrupter springs of the stepping magnet 350, and winding of said magnet to battery. The operation now depends upon whether the register set with which the wipers of the line switch are in connection is busy or is not busy. If this register set is busy, the test contact such as 346, associated therewith will have a ground potential upon it, the switching relay 204 will be short circuited by way of armatures 226 and 221, and the stepping magnet 350 which interrupts its own circuit, will operate as a buzzer to advance the switch wipers 335 to 340, inclusive, step-by-step in search of an idle register set. This operation will continue as long as the test wiper 340 continues to engage grounded or busy test contacts. However, we may assume that in the present case the register set shown in Fig. 4, is idle, and the test contact 346 therefore is not grounded, and therefore no rotation of the lineswitch C' will take place. The switching relay 204 is at once energized over the above traced circuit, and said relay at armature 225 opens a point in the circuit of busy relay 210 so that the busy relay will not energize when ground is connected to conductor 263. At armature 226 and its working contact, relay 204 connects ground to the release trunk conductor 265 thereby rendering the register set shown in Fig. 4, busy to other register selectors such as C' which have access thereto, and at armature 227 and its working contact, relay 204 prepares a point in the circuit for energizing relays 205 and 208 and the call lamp CL.

When the register selector C' seizes the register set in Fig. 4, it will be remembered that the switching relay 204 of the cord circuit O connects ground to bank contact 346, in order to render the register set shown in Fig. 4 busy to other register selectors. When the register set is seized and ground is connected to bank contact 346 relay 406 is energized and said relay at armature 432 prepares a locking circuit for relay 407 and at armature 431 closes a circuit for energizing relay 400 of the first register R¹ as follows: from ground by way of working contact of armature 431 and said armature, armature 716 and its resting contact of the transfer relay 705 of the register R⁴, armature 616 and its resting contact of transfer relay 605 of register R³, armature 516 and its resting contact of the transfer relay 505 of the register R², armature 416 and its resting contact of transfer relay 405 of the register R¹, and winding of relay 400 to battery. Relay 400 is energized over the above traced circuit and at armatures 412 to 415, inclusive, prepares the circuits for the storage relays 401 to 404, inclusive, of the register R¹. Due to the operation of relay 400 the register R¹ is now in condition to receive the digit designation 130

which is being or has been dialled up on the relay group shown in Fig. 3.

The calling subscriber may continue dialling even though the register selector has not selected an idle register set, or in other words the apparatus is ready for the receipt of impulses corresponding to the second digit of the local number of the called line in the manual exchange at any time after the seizure 10 of the cord circuit O. When the dial of the calling device S is operated in accordance with the next digit another series of interruptions, three in this case, will be produced in the line circuit and will bring about a like 15 series of deenergizations of the line relay 101 in the repeater E, which results in a like series of interruptions in the circuit of the line relay 202 of the cord circuit O. Each time line relay 202 falls back an impulse is 20 transmitted over conductors 260 and 261. The grounded impulses over the conductor 261 maintains the slow acting relay 300 energized for the duration of the series of impulses and the latter relay maintains the circuit of slow to release relay 301 closed for a 25 slightly longer period for the purpose described hereinafter. Relay 301, upon energizing, at armature 309 and its working contact grounds the common conductor 334.

30 The relays 302, 303, 304, 305 and 306 of the relay group RG are two step relays and said relays operate only their armatures 311, 316, 320, 325, 330, respectively, on first step. When ground is connected to conductor 260 35 for the first impulse, a circuit for energizing relay 302 in its first step may be traced as follows: from ground by way of the working contact of armature 220 and said armature, resting contact of armature 217 and said armature, conductor 260, armature 319 and its resting contact, armature 315 and its resting contact, armature 310 and its resting contact, and upper winding of relay 302 to battery. Relay 302 energizes over the above 40 traced circuit and closes only the working contact of armature 311. When ground is removed from the impulse conductor 260 at the end of the first impulse a circuit may be traced for completely energizing relay 302 as 45 follows: from grounded conductor 334, armature 321 and its resting contact, armature 311 and its working contact, and through the lower and upper windings of relay 302 to battery. Relay 302, upon completely energizing, 50 transfers the impulse conductor to the second counting relay, or relay 303. The next time the impulse conductor 260 is grounded relay 303 operates in its first step and closes only the armature 316 and when 55 the ground is removed from the impulse conductor 260, relay 303 operates in its second step to transfer the impulse conductor 260 to the third counting relay, or relay 304. The 60 circuits for completely energizing relay 303 65 may be traced as follows: from grounded con-

ductor 334, armature 332 and its resting contact, resting contact of armature 331 and said armature, armature 316 and its working contact, and through the lower and upper windings of relay 303 to battery. When ground is connected to impulse conductor 260 for the third impulse, relay 304 energizes in its first step to close its armature 320. When ground is removed from impulse conductor 260 at the 70 end of the third impulse, relay 304 energizes in its second step over the following circuit: from grounded conductor 334, armature 332 and its resting contact, armature 320 and its working contact, and through the lower and upper windings of relay 304 to battery. Relay 304 at armature 319 transfers the impulse conductor 260 to the fourth counting relay or relay 305, and at armature 321 75 opens the locking circuit of the first counting relay 302 thereby causing said relay to deenergize. At the end of the third impulse only 80 relays 303 and 304 are energized and said relays remain in energized position until ground is removed from conductor 334 at the end of 85 the digit as will be described hereinafter. 90

It has previously been explained how the relays 300 and 301 are maintained energized for the duration of the impulses for each digit and therefore shortly after the last impulse has 95 been received slow to release relay 300 deenergizes. Relay 301 being also a slow-acting relay maintains its armatures 308 and 309 closed for a short interval after its circuit is 100 opened and during such time a circuit may be traced for transferring the stored designation of the relay group RG to the register set R¹ Fig. 4. The circuit for transferring such 105 designation may be traced as follows: from ground, armature 307 and its resting contact, working contact of armature 308 and 110 said armature, conductor 263, armature 225 and its working contact, conductor 262, armature 318 and its working contact, armature 333 and its resting contact, wiper 337 of the register selector C', 115 bank contact 343, conductor 452, Fig. 4, working contact of armature 414 and said armature, and winding of relay 402 to battery. Relay 402, upon energizing, closes at armature 419 a locking circuit for itself which 120 includes the winding of transfer relay 405 of the register R¹ and ground at armature 431. Transfer relay 405 is not energized at this time because said relay is short circuited from 125 ground on conductor 452. Relay 402 at armatures 420 and 421 prepares a circuit for lighting certain of the indicating lamps at the operator's position.

Shortly after relay 300 deenergizes, relay 130 301 also deenergizes and at armature 309 the latter relay opens the locking circuit of relays 303 and 304 whereupon said relays deenergize. At armature 308 relay 301 removes ground from the conductor 452 Fig. 4, thereby removing the short circuit from 135

- around the transfer relay 405. Transfer relay 405 now energizes over the following circuit: from ground, working contact of armature 431 and said armature, winding of relay 405, armature 419 and its working contact, and winding of relay 402 to battery. Transfer relay 405, upon energizing, at armature 416 and its resting contact opens the circuit of relay 400 of the register R¹ and at 10 the same armature and its working contact closes a circuit for the relay 500 of the register R². Relay 400 deenergizes and disconnects the storage relays of the register R¹ from the conductors 450 to 453, inclusive.
- 15 The circuit for energizing relay 500 of the register R² may be traced as follows: ground, working contact of armature 431 and said armature, armature 716 and its resting contact, armature 616 and its resting contact, 20 armature 516 and its resting contact, armature 416 and its working contact, and winding of relay 500 to battery. Relay 500 of the register R² corresponds to the relay 400 in the register R¹ and therefore relay 500, upon 25 energizing, at armatures 512 to 515, inclusive, prepares the circuits for the storage relays 501 to 504 inclusive, which relays correspond in every detail to the storage relays 401 to 404, inclusive, of the register R¹. The register R² is now in condition to receive the 30 digit designations of the third digit.
- When the third digit, or the digit 4, is dialled, relays 300 to 304, inclusive, are operated in the same manner as previously explained. At the start of the fourth impulse, however, relay 305 is energized in its first step and at armature 325 it prepares a locking circuit for itself which includes the armature 321 and the grounded conductor 334.
- 40 At the end of the fourth impulse ground is removed from conductor 260 and relay 305 completely energizes over the above mentioned locking circuit. At armature 324 relay 305 transfers the impulsing circuit to relay 306 and at armature 327 prepares a circuit for grounding conductor 451.
- When relay 300 deenergizes, after the cessation of impulses, ground is connected momentarily to conductors 451 and 452 as follows: ground by way of armature 307 and its resting contact, working contact of armature 308 and said armature, conductor 263, armature 225 and its working contact, conductor 262, to armatures 314 and 318 where 50 the circuit divides, one branch extending by way of armature 314 and its resting contact, armature 327 and its working contact, wiper 336, bank contact 342, to conductor 451; the other branch extending by way of armature 318 and its working contact, armature 333 and its resting contact, wiper 337, bank contact 343, to conductor 452. When ground is connected to conductor 451 a circuit may be traced through the working contact of armature 513 to relay 503 of register 55 R² and said relay will thereupon energize and lock up in the same manner as explained for relay 402 of the register R¹. Ground on conductor 452 causes the energization of storage relay 502 of the register R² in a similar manner. Relays 502 and 503 of the register R² energize and prepare circuits at their armatures for the indicating lamps in the same manner as explained for register R¹. Although the relays of register R² are not shown the circuits will be readily understood in view of the showing of register R¹.
- When relay 301 deenergizes after the last impulse, counting relays 303, 304 and 305 deenergize. Ground is also removed from conductors 451 and 452 whereupon a circuit is closed for the transfer relay 505 of the register R² from ground at armature 431, winding of relay 505 through armatures 519 and 522, which correspond to armatures such as 65 armatures 419 and 422, and through the winding of relays 502 and 503 in parallel to battery. Relays 502, 503 and 505 are maintained energized over the above traced circuit. Relay 505, upon energizing, at armature 516 and its resting contact opens the circuit of relay 500 which deenergizes, and at its working contact closes an energizing circuit for the relay 600 of the register R³, whereupon the latter relay energizes and prepares 70 the register R³ for storing the digit designation of the fourth digit to be dialled.
- When the fourth digit is dialled, or the digit 5, relays 300 to 305 energize in the same manner as previously described. When ground is connected to conductor 260 at the start of the fifth impulse, relay 306 is energized in its first step over a circuit including the armatures 324 and 319 and the conductor 260. Relay 306, upon energizing in its first 75 step, prepares at armature 330 a locking circuit for itself. When ground is removed from the impulse conductor 260, at the end of a fifth impulse, relay 306 becomes fully energized over a circuit including a grounded conductor 334, armature 330 and the lower and upper windings of relay 306. Relay 306, upon fully energizing, prepares at armature 329 the impulsing circuit to the first counting relay, or relay 302, at armature 331 opens the locking circuit of relay 303 whereupon said relay deenergizes, and at armature 332 opens the locking circuit of relay 304 whereupon said relay deenergizes. At armature 333 relay 306 prepares a circuit for grounding one or more of the conductors extending to the register set.
- When relay 300 deenergizes after the fourth digit ground is momentarily connected to conductor 451 by way of conductor 263, conductor 262, armature 318, armature 327, wiper 336, and bank contact 342 to conductor 451. A circuit may now be traced for energizing storage relay 603 of register R³ as follows: 100 grounded conductor 451, working contact of

armature 613 and said armature, and winding of storage relay 603 to battery. Relay 603 of register R^3 outperforms the same functions as relay 403 of the register R^1 . Shortly after relay 300 deenergizes, relay 301 also deenergizes and at armature 309 disconnects ground from conductor 334 thereby permitting all of the counting relays in the relay group RG to deenergize. Relay 301 at armature 308 10 also removes ground from conductor 451 whereupon transfer relay 605, which heretofore has been short circuited, is energized. Relays 603 and 605 are maintained energized over a circuit similar to the locking circuit of 15 relays 402 and 405 described for register R^1 . Relay 605, upon energizing, at armature 616 and its resting contact opens the circuit of relay 600 which deenergizes and at its working contact closes a circuit for energizing 20 relay 700 of the register R^4 . Relay 700 of the register R^4 energizes and at armatures 712 to 715, inclusive, prepares the register R^4 for receipt of the next digit designation.

When the last digit, or the digit 6, of 25 the wanted subscriber's number is dialled, relays 300 to 306 energize in the same manner as previously explained. It will be remembered that relays 305 and 306 were the only relays in the relay group R^3 which were in 30 operated position after the end of the fifth impulse. When ground is connected to the impulse conductor 260 at the start of the sixth impulse relay 302 is energized in its first step. When ground is removed from 35 impulse conductor 260 after the end of the sixth impulse a circuit may be traced from the grounded conductor 334 by way of either armature 332 or armature 321, armature 311 and its working contact, and through the 40 lower and upper windings of relay 302 to battery. Relay 302, upon energizing in its second step, at armature 310 and its working contact transfers the impulse conductor to the second counting relay, or relay 303. At 45 armature 312 and its working contact relay 302 prepares a locking circuit for counting relay 304, and at armature 312 and its resting contact opens one of the locking circuits for the counting relay 305. The latter relay, however, does not deenergize because 50 it remains locked up through armature 317 and its resting contact. At armature 313 relay 302 prepares a locking circuit for the relay 303, and at armature 314 and its working contact prepares a circuit for grounding the conductor 453 of the register set.

Relay 300, upon deenergizing shortly after 55 the end of the sixth impulse, closes at armature 307 a circuit for momentarily grounding the conductors 451 and 453 of the register set. It will be remembered that relays 302, 305 and 306 of the relay groups RG are the only relays in operated position and therefore when conductor 262 is momentarily grounded as previously explained, ground is

connected by way of armature 314 and its working contact, armature 323 and its resting contact, wiper 338, bank contact 344, to conductor 453; and from ground through armature 318 and its resting contact, armature 327 and its working contact, wiper 336, bank contact 342, to conductor 451. 70

When conductors 451 and 453 are momentarily grounded, relays 703 and 701 are energized by way of armatures 713 and 715, 75 respectively, in the same manner as previously explained for the corresponding relays of the register R^1 . Relays 701 and 703 upon energizing, close circuits at their respective armatures for controlling the indicating 80 lamp at register R^4 .

Relay 301, upon deenergizing, at armature 309 removes ground from conductor 334 thereby deenergizing relays 302, 305 and 306 of the relay group RG. At armature 308 relay 301 disconnects ground from conductors 451 and 453 thereby permitting transfer relay 705 which heretofore has been short circuited to energize. The circuit for energizing relay 705 may be traced as follows: from 90 grounded armature 431 through the winding of relay 705 and the windings of relays 701 and 703 to battery. Transfer relay 705, upon energizing, opens at armature 716 and its resting contact the circuit of relay 700 of 95 the register R^4 and at its working contact closes a circuit from ground, by way of armature 431 for energizing the relay 408. Relay 408 energizing, at armature 436 and its working contact, completes an energizing 100 circuit for the start relay 409 of the consecution control switch CCS, at armature 437 and its working contact prepares a circuit for the lamp relay 407, and at its resting contact removes ground from the bank contact 447 which corresponds to the register set shown in Fig. 4. At armature 438 and its working contact, relay 408 completes a circuit for lighting the pilot lamp PL thereby 105 notifying the operator that a call has been registered on the associated register set. Conductor 445 may be considered as a test conductor and extends to the first contact of the bank in the consecution control switch CCS, since the register set shown is assumed 110 to be the first register set at the position. The other test conductors directly above conductor 445 are of course associated with the other register sets at the same position and are all normally connected to ground through 115 armatures such as armature 437 of relay 408. 120

Assuming that no other call is being shown on the indicating device just at the present time, the consecution control switch CCS is 125 immediately operated to switch the registered call over onto the indicating device. The operation is as follows: when relay 409 energizes, it connects up the wiper 446 by means of armature 440, and at armature 439 closes a circuit for the slow acting line relay 130

411. Upon energizing, the latter relay closes a circuit at its armature 443 which includes the switching relay 410 and the stepping magnet 449 in series, and at its armature 444 connects the wiper 446 to the above circuit at a point midway between said relay and magnet. The latter operation provides for advancing the wiper 446 in case the contact with which it is in engagement is grounded, but it will be assumed in the present case that the wiper is standing on the first contact of the bank as shown in the drawing, and since the ground has been removed from bank contact 449 by the energization of relay 408, no rotation of the switch will take place. Instead, the switching relay 410, which is of high resistance, is at once energized in series with the stepping magnet 447, the latter remaining inoperative, and opens the circuit of the line relay at armature 441. The line relay is slow acting, however, and before it has had time to fall back, relay 407 is energized over the following circuit; from ground, by way of armature 443 and its working contact, working contacts of armature 442 and said armature, armature 440 and its working contact, wiper 446, bank contact 447, armature 437 and its working contact, and the winding of relay 407 to battery. Upon energizing, relay 407 locks itself to the grounded armature 432 at its armature 435. This operation connects ground to conductor 445 for maintaining switching relay 410 energized after the line relay 411 becomes deenergized. Relays 407 and 408 are now both energized, and the consecution control switch is in operated position (switching relay energized) with its wiper in engagement with bank contact 447 which corresponds to the first register set or the register set shown in Fig. 4. Other calls may be registered on the other register sets at any time now and when registration is completed, the lamps, such as pilot lamp PL, corresponding to the register sets in use will be lighted, but this has no effect on the consecution control switch CCS, which makes no further movement until the call on the first register set has been disposed of.

Relay 407 is the relay which switches over the registered call to the lamps of the indicating device and the manner in which this is done will now be pointed out. When the storage relay 402 of the register R¹ was operated, it prepared at its armature 421 a circuit for indicator lamp #3 of the register R¹, extending by way of grounded armature 433 of relay 407, armature 418 and its resting contacts, armature 421 and its working contact, armature 424 and its resting contact, armature 428 and its resting contact, lamp #3 to battery. When the relays 502 and 503 of the register R² were operated, a circuit was prepared for the lamp #4 of the register R². This circuit extends from the grounded armature 433, armature 518 and its resting con-

tact which corresponds to armature 418 of the register R¹, armature 521 and its working contact which corresponds to the armature 421 of the register R¹, armature 524 and its working contact which corresponds to the armature 424 of the register R¹, lamp #4 to battery. The operated relays in the registers R³ and R⁴ close circuits from grounded armature 433 to the #5 lamp of the register R³ and the #6 lamp of the register R⁴ in a similar manner. Therefore, when relay 407 connects ground to armature 433 the number 3 indicating lamp of register R¹, the #4 indicating lamp of the register R² the number 5 indicating lamp of the register R³ and the number 6 indicating lamp of the register R⁴ light to inform the operator that the called line is #3456.

The manner in which the operator handles the call thus displayed before her will now be considered. When relay 407 pulls up and closes a circuit for displaying the registered number to the operator, it also closes at its armature 434 a circuit for the trunk or call lamp CL in the cord circuit O which may be traced as follows: from ground by way of armature 434 and its working contact, bank contacts 345, wiper 339, conductor 264, working contact of armature 227 and said armature, winding of relay 208, resting contact of armature 234 and said armature, armature 229 and its resting contact, call lamp CL to battery. By the closure of the above circuit, call lamp CL which is individual to the cord circuit O, is lighted simultaneously with the call indicating lamps, thus enabling the operator to know which one of her cord circuits is being used by the automatic subscriber whose wanted number is at this particular time being shown on the indicating lamps. Simultaneously with the lighting of the call lamp CL, relays 208 and 205 are energized, the latter relay being energized in parallel with relay 208 by way of armature 231 and its resting contact. Relay 205, upon energizing, prepares at armatures 228 the circuit for the busy relay 210. Relay 208, upon energizing, opens the circuit of supervisory lamp SL at armature 236.

Having observed the #3456 and knowing by the lighting of the lamp CL that the cord circuit O is the one in use, the operator will test the multiple jack of the line number 3456 with the tip of her plug in the usual manner in order to find out whether or not the line is busy.

If the line is found to be in use, the operator will hear the well known busy click in her receiver when she tests the called line and will therefore operate the busy key K. By the operation of the busy key K ground is connected to common conductor 252 which extends by way of armature 228 and its working contact, resting contact of armature 244 and said armature, and winding of relay 210 to

battery. Relay 210 energizes over the above traced circuit and at armature 239 and its working contact connects the busy tone to the upper left hand winding of the repeating 5 coil and to the conductor 130, thereby transmitting the busy tone to the calling subscriber in the well known manner. Relay 210 at armature 241 completes a locking circuit for itself which may be traced as follows: from ground, armature 224 and its 10 working contact, armature 235 and its resting contact, armature 241 and its working contact, and winding of relay 210 to battery. In addition to the above, relay 210 at armature 15 240 opens the circuit of the stepping magnet 350 of the register selector C' and also opens the circuit of the switching relay 204 at armatures 240 and 241 whereupon the latter relay deenergizes. Relay 204, upon deenergizing, at armature 227 opens the circuit of relays 205, 208, and call lamp CL. At armature 225 relay 204 prepares a circuit for the busy relay 210 which will be explained more fully hereinafter. In addition to the 20 above, relay 204 at armature 226 disconnects ground from release trunk conductor 265 thereby causing relay 406 Fig. 4, to deenergize. Relay 406, upon deenergizing, at armature 432 opens the circuit of relays 407 and 30 410 whereupon said relays deenergize. At armature 431, relay 406 opens the circuit of the operated storage relays in the registers R¹ to R⁴, inclusive, and the relay of 408. Relay 407, upon deenergizing, at armature 35 433 opens the circuit to all of the indicating lamps of the registers R¹ to R⁴, inclusive, and at armature 434 disconnects ground from bank contact 345. Relay 408, upon deenergizing, at armature 436 opens the circuit of 40 relay 409 whereupon said relay deenergizes, and at armature 437 again applies ground to the bank contacts 447 in the consecution control switch CCS. In addition, relay 408 at armature 438 opens the circuit of the pilot 45 lamp PL. All of the relays and apparatus in the register set shown in Fig. 4 has been returned to normal position in readiness to receive the digits of the next call.

Having described how the calling subscriber receives the busy tone and how the register set is released responsive to the operation of the busy key a description will now be given explaining how the connection is completed to the called subscriber when the operator 50 finds the line of the called subscriber idle. After testing, if the line is idle, the operator will at once insert the plug P into the jack of the wanted line which in the present place is the jack J. As soon as the plug is inserted in 55 the jack J a circuit is completed for the sleeve relay 211 in series with cut off relay 250 of the called line, and the latter relay is energized to clear the line of its normal battery and ground connections in the usual manner. 60 Relay 211 is energized also and at armature 65

243 completes a circuit for energizing relay 206, at armature 244 opens a point in the circuit of the busy relay 210, and at armature 245 disconnects the operator's head set. At the same time at armatures 242 and 245 the 70 tip and ring conductors of the cord circuit are connected through to the plug, and a ringing circuit is established over which ringing current from the generator GEN. is projected intermittently to signal the called subscriber. 75

In addition to the function described, relay 206 energizes over the above traced circuit and said relay at armature 229 opens the circuit of the call lamp CL and relay 208 which thereupon deenergize. At armature 230, relay 206, connects ground to the lower winding of line relay 202, at armatures 232 prepares a circuit for the supervisory lamp SL, and at armature 231 and its resting contact opens the circuit of relay 205 which deenergizes and opens the circuit to the busy relay. At armature 231 and its working contact relay 206 closes a circuit for relay 207. Relay 207 is now energized over the following 80 circuit:—from ground by way of armature 434 and its working contact, bank contact 345, wiper 339, conductor 264, working contact of armature 227 and said armature, armature 231 and its working contact, working contact of armature 223 and said armature, through normally closed springs controlled by armature 235, and winding of relay 207 to battery. At armature 233 relay 207 opens the circuit extending to the stepping magnet 350 of the register selector C' thereby also 85 opening the energizing circuit of relay 204 which deenergizes. At armature 234 relay 207 opens a further point in the circuit of relay 208 and prepares a circuit for flashing the call lamp CL in case the operator removes the plug P from the jack J before the calling man has hung up, and at armature 235 closes a locking circuit for itself in place of its 90 original energizing circuit. Relay 204, upon deenergizing, removes ground from release trunk conductor 265 thereby releasing the apparatus shown in Fig. 4, in the same manner as previously described. 95

Having explained how the connection has 100 been completed to the called subscriber A', and how ringing current is projected out over the called line to signal the subscriber, a description will now be given of the operations which take place when the called subscriber at substation A answers. During the ringing operation a tone is induced in the left hand winding of the repeating coil of the cord circuit O by reason of the fact that the ringing circuit includes the lower right hand winding 105 of the repeating coil, and this tone is audible to the calling subscriber who is thus advised that the signalling operation is proceeding satisfactorily. The ring cut-off relay 209 is included in the ringing circuit, and when the 110 115 120 125 130

called subscriber answers, this relay pulls up and locks itself in series with the sleeve relay 211. Relay 209 also breaks the ringing circuit at armature 237, and at the working contact of the same armature finally completes the talking circuit. The transmitter at the called station is now supplied with talking current through the right hand windings of the repeating coil and through the upper and lower windings of battery feed relay 200. Relay 200 energizes in the first instant through its lower winding alone, since the upper winding is normally short circuited in order to keep it out of the ringing circuit, but when the relay pulls up both its windings are inserted in the battery feed circuit. In energized position, relay 200 closes a circuit for the reversing relay 201. Upon energizing, relay 201 reverses the trunk conductors 130 and 131 as regards their connections with the windings of the line relay 202, and the direction of current flow in the trunk line is thus reversed. The direction of current flow through the lower winding of the electro-polarized relay 105 at the repeater E is therefore reversed and this relay is now operated. At armature 119 relay 105 completes a circuit for the reversing relay 100. The operation of relay 100 reverses the direction of current flow in the calling line. This operation may be used for operating a meter, or for other similar purposes, and is provided in accordance with standard practice although it is of no utility in the particular system shown herein.

The required connection having been established, the subscribers may now converse as desired. When the conversation is finished both subscribers will hang up their receivers, and the replacement of the receiver at the calling station A causes the automatic switches to be restored to normal. When the receiver is replaced the circuit of the line relay 101 is broken, resulting in the deenergization of this relay and also the deenergization of the slow acting relay 102. Line relay 101, on deenergizing, opens the bridge across the trunk conductors 130 and 131, and at armature 110 opens the circuit of slow to release relay 102 its working contact. Relay 101 at armature 110 and its resting contact completes the circuit for energizing slow to release relay 103. A short interval after the line relay releases slow to release relay 102 deenergizes and at armature 112 the latter relay removes ground from the release trunk conductor 77 thereby permitting the automatic switches in the automatic exchange to release. At armature 115 relay 102 opens the circuit of slow to release relay 103 and at armature 114 and its working contact opens the circuit of slow relay 104. At its resting contact of the same armature relay 102 substitutes a circuit for maintaining relay 104 energized over conductor 131 until the plug P is withdrawn from the jack

J. A short interval after relay 102 deenergizes, relay 103 also deenergizes and at its armature 117 again connects ground to the release trunk conductor 77 by way of armature 120 and its working contact to busy the repeater E to the automatic switches in the automatic exchange. 70

When the bridge across the trunk conductors 130 and 131 is broken at armature 111 line relay 202 is deenergized. Relay 202, on deenergizing, opens the circuit of slow to release relay 203 at armature 218 whereupon said relay deenergizes. Relay 203, on deenergizing, opens the locking circuit of relay 207 at armature 224 and its working contact 80 whereupon the latter relay deenergizes. At armature 224 and its resting contact relay 203 closes a circuit for lighting the supervisory lamp SL thereby indicating to the operator that the calling party has replaced his receiver. At armature 224 and its working contact relay 203 also opens the circuit of the reversing relay 201. 85

When the operator observes the lighted supervisory lamp SL she will remove the plug of the cord circuit O from the jack and relays 209 and 211 are deenergized and restored to normal. At armature 243 relay 211 opens the circuit of relay 206 whereupon the latter relay deenergizes. At armature 230 95 and its working contact, relay 206 removes the ground connection which extended by way of lower winding of line relay 202, normal closed contacts controlled by armature 215, and lower left-hand winding of repeating coil to trunk conductor 131 and over the previously traced circuit for maintaining relay 104 energized. Relay 104, upon deenergizing, at armature 120 and its working contact disconnects ground from the release trunk conductor 77, thereby removing the busy condition. All the apparatus has now been restored and is ready for use in handling another call. 100

In case the operator should accidentally withdraw the plug from the jack before the automatic subscriber has hung up his receiver, means is provided for flashing the call lamp CL to call her attention to the error. When a plug is withdrawn relays 206, 209 and 211 are deenergized, and since relay 207 is now in energized position, the calling subscriber not having hung up his receiver, a circuit is completed for the call lamp CL which includes the interrupter I, 110 and the lamp will be flashed to attract the attention of the operator. If the operator remembers the jack from which the plug was withdrawn, she can replug immediately, otherwise she will plug into a special jack 120 (not shown) which connects with her headset so that she can talk to the calling party and ask him what number he was disconnected from. 125

Certain details of the system will now be 130

explained which it was not convenient to go into before, and the first thing which will be considered is the manner in which a calling subscriber is given the busy signal if all the register sets are in use. It will be remembered that relays 300 and 301 are energized during the transmission of impulses for each digit and that shortly after the last impulse of the second digit has been sent relay 300 deenergizes and connects ground at armature 307 to conductor 263. If at this time the register selector C' has not yet seized an idle register set, the switching relay 204 in the cord circuit O will not be energized. A circuit may then be traced for operating the busy relay 210 of the cord circuit O as follows: from ground by way of armature 307 and its resting contact, working contact of armature 308 and said armature, conductor 263, armature 225 and its resting contact, resting contact of armature 244 and said armature, and winding of busy relay 210 to battery. Relay 210, upon energizing, at armature 240 opens the circuit of the stepping magnet 350 of the register selector C' and at armature 241 and its working contact closes a locking circuit for itself which includes the armature 224 so that when relay 301, Fig. 3, deenergizes and removes ground from conductor 263, the busy relay will be maintained in operated position. At armature 239 and its working contact relay 210 connects the busy tone to the trunk and the busy tone is transmitted to the calling subscriber in the well known manner.

The next thing to be considered is the novel circuit arrangement by means of which the B operator by the simple expedient of removing her plug P' from the jack 254, when she desires to leave her position, may busy the incoming trunks to her position. When the operator removes her plug P' from the jack 254 relay 248 deenergizes and at its armature closes a circuit for energizing relay 249. Relay 249, upon energizing, connects ground to conductors such as conductor 253. When ground is connected to conductor 253 a circuit may be traced for energizing relay 104 of repeater E as follows: by way of the lower winding of line relay 202, normally closed springs controlled by armature 215, lower left hand winding of the repeating coil, conductor 131, resting contact of armature 114 and said armature, and winding of relay 104 to battery. Relay 104 energizes, but relay 202 due to the high resistance of relay 104 does not energize. Relay 104 at armature 120 connects ground to release trunk conductor 77 thereby rendering the trunk busy to the automatic switches in the automatic exchange. In the same manner ground on the other conductors, such as conductor 253, causes the remaining trunks extending to this particular B operator's position to become

busy to the switches in the automatic exchange.

Having described my invention, what I consider to be new and desire to have protected by Letters Patent will be pointed out in the appended claims.

What I claim as my invention is:

1. In a telephone system, a manual exchange and an automatic exchange, a trunk line accessible to automatic switches in the automatic exchange and terminating in a cord circuit at the manual exchange, a plurality of register sets each comprising a series of relay groups for registering the digits in the telephone numbers of manual lines called over said trunk line, a switch individual to said cord circuit, means in said cord circuit operated responsive to the seizure of said trunk line for causing said individual switch to hunt for an idle one of said register sets, and means in the manual exchange for registering the first digit in the telephone number of the called manual line even though said individual switch has not selected an idle register set.

2. In a telephone system, a manual exchange and an automatic exchange, a trunk line accessible to automatic switches in the automatic exchange and terminating in a cord circuit at the manual exchange, a plurality of register sets each comprising a series of relay groups for registering the digits in the telephone numbers of manual lines called over the trunk line, a switch individual to said cord circuit, means in said cord circuit operated responsive to the seizure of said trunk line for causing said individual switch to hunt for an idle one of said register sets, and means in the manual exchange for registering the first digit in the telephone number of the called line during the time said individual switch is hunting for an idle register set.

3. In a telephone system, a manual exchange and an automatic exchange, a trunk line accessible to automatic switches in the automatic exchange and terminating in a cord circuit at the manual exchange, a plurality of register sets each comprising a series of relay groups for registering the digits in the telephone numbers of manual lines called over said trunk line, a switch individual to said cord circuit, means in said cord circuit operated responsive to the seizure of said trunk line for causing said individual switch to hunt for an idle one of said register sets, a group of counting relays individual to said cord circuit for counting the impulses in the first digit of the called telephone number regardless of whether said individual switch has selected an idle register set or not, and means operated after the first digit for transferring the first digit to the first relay group in the selected register.

4. In a telephone system, a manual ex-

- change and an automatic exchange, a trunk line accessible to automatic switches in the automatic exchange and terminating in a cord circuit at the manual exchange, a plurality of register sets each comprising a series of relay groups for registering the digits in the telephone numbers of manual lines called over said trunk line, a switch individual to said cord circuit, means in said cord circuit operated responsive to the seizure of said trunk line for causing said individual switch to hunt for an idle one of said register sets, a group of counting relays individual to said cord circuit for counting the impulses in the first digit of the called telephone number regardless of whether said individual switch has selected an idle register set or not, and means operated after the first digit for causing the busy tone to be transmitted to the calling party in case said individual switch has not at such time selected an idle register set.
5. In a telephone system, a manual exchange and an automatic exchange, a trunk line accessible to automatic switches in the automatic exchange and terminating in a cord circuit at the manual exchange, a plurality of register sets each comprising a series of relay groups for registering the digits in the telephone numbers of manual lines called over said trunk line, a switch individual to said cord circuit, means in said cord circuit operated responsive to the seizure of said trunk line for causing said individual switch to hunt for an idle one of said register sets, a group of counting relays individual to said cord circuit for counting the impulses in the first digit of the called telephone number regardless of whether said individual switch has selected an idle register set or not, and means operated after the first digit for causing the busy tone to be transmitted to the calling party in case all of the register sets are busy.
45. In a telephone system, a manual exchange, trunk lines terminating in cord circuits in said exchange, automatic substations having access to said trunk lines for calling the subscribers in the manual exchange, a plurality of register sets for registering the telephone numbers of called manual stations, automatic switching mechanisms for connecting any cord circuit with an idle register set when the cord circuit is taken into use, and a register individual to each cord circuit for receiving the digits of a called number and for transferring each digit to the selected register set after receipt thereof.
7. In a telephone system, a manual exchange, trunk lines terminating in cord circuits in said exchange, automatic substations having access to said trunk lines for calling the subscribers in the manual exchange, a plurality of register sets for registering the telephone numbers of called manual stations, automatic switching mechanisms for connecting any cord circuit with an idle register set when the cord circuit is taken into use, and a group of counting relays individual to each cord circuit upon which successive digits are counted and are then transferred to the selected register set.
8. In a telephone system, a manual exchange, trunk lines terminating in cord circuits in said exchange, automatic substations having access to said trunk lines for calling the subscribers in the manual exchange, a plurality of register sets for registering the telephone numbers of called manual stations, automatic switching mechanisms for connecting any cord circuit with an idle register set when the cord circuit is taken into use, a group of relays individual to each cord circuit upon which each digit of the called number is temporarily stored, and means operated after each digit for transferring the stored digit to the selected register set.
9. In a telephone system, a manual exchange, trunk lines terminating in cord circuits in said exchange, automatic substations having access to said trunk lines for calling the subscribers in the manual exchange, a plurality of register sets for registering the telephone numbers of called manual stations, automatic switching mechanisms for connecting any cord circuit with an idle register set when the cord circuit is taken into use, a group of counting relays individual to each cord circuit upon which each successive digit of the called number is temporarily stored, and means operated after each digit for transferring the successively stored digits to successive relay groups of the selected register set, respectively.
10. In a telephone system, a manual exchange, trunk lines terminating in cord circuits in said exchange, automatic substations having access to said trunk lines for calling the subscribers in the manual exchange, a plurality of register sets for registering the telephone numbers of called manual stations, automatic switching mechanisms for connecting any cord circuit with an idle register set when the cord circuit is taken into use, and a relay group individual to each cord circuit repeatedly operated responsive to the successive digits in the called number for successively controlling the setting of the relay groups of said selected register set.
11. In a telephone system, two conductor trunk lines extending from an automatic exchange and terminating in cord circuits at an operator's position in a manual exchange, a relay in each trunk line at the automatic exchange for making its associated trunk line busy when energized, an operator's plug and jack common to said cord circuits for connecting her head-set to said cord circuits, and means operated responsive to the disconnection of said plug from said jack when the

- operator desires to leave her position for closing a circuit over only one of the conductors of each of said trunks for energizing said relays.
- 5 12. In a telephone system, a trunk line, a register set associated with said trunk line, a digit receiving device individual to and controlled over said trunk line, and means for transferring each digit from the receiving device to the register set as soon as received. 70
- 10 13. In a telephone system, a trunk line, a storage set associated with said trunk line, a group of counting relays individual to said trunk line, means in said relay group for counting the number of impulses in each successive digit of a called telephone number received over said trunk line, and means for transferring each digit from the relay group to the storage set as soon as received. 75
- 15 14. In a telephone system, a trunk line, a storage set comprising a plurality of relay groups associated with said trunk line, a digit receiving device individual to said trunk line, means for sending digits over said trunk line to said receiving device, and means for transferring each digit from the receiving device to successive relay groups in the storage set as soon as such digits are received. 80
- 20 14. In a telephone system, a trunk line, a register set comprising a plurality of relay groups associated with said trunk line, a group of counting relays individual to said trunk line, means in said counting relay group for counting the number of impulses in each successive digit of a called telephone number received over the trunk line, and means for transferring each digit from the counting relay group to successive relay groups in the register set as soon as received. 85
- 25 15. In a telephone system, a trunk line, a register set comprising a plurality of relay groups associated with said trunk line, a group of counting relays individual to said trunk line, means in said counting relay group for counting the number of impulses in each successive digit of a called telephone number received over the trunk line, and means for transferring each digit from the counting relay group to successive relay groups in the register set as soon as received. 90
- 30 16. In a telephone system, a plurality of trunk lines, a plurality of storage sets common to said trunk lines, a plurality of relay groups in each storage set, a digit receiving device individual to each trunk line for registering digits transmitted over said trunk line, and means for transferring each digit from the receiving device to successive relay groups in any one of said storage sets as soon as such digits are received. 95
- 35 17. In a telephone system, a plurality of trunk lines, a plurality of storage sets common to said trunk lines, a plurality of relay groups in each storage set, a digit receiving device individual to each trunk line, means for transferring each digit from the receiving device to successive relay groups in any one of said storage sets as soon as such digits are received, and means operated after the first digit for causing the busy tone to be transmitted to the calling subscriber in case all the storage sets are busy. 100
- 40 18. In a telephone system wherein the digits of called telephone numbers are stored on storage sets common to a plurality of trunk lines, means individual to each of said 105
- 45 19. In a telephone system wherein the digits of called telephone numbers are stored on storage sets common to a plurality of trunk lines, a group of counting relays individual to each of said trunk lines, and means controlled by any one of said counting relay groups for registering the number of impulses in each successive digit of the called number and for transferring such registrations to one of said common storage sets after each digit. 110
- 50 20. In a telephone system wherein the digits of called telephone numbers are stored on storage sets common to a plurality of trunk lines, a group of counting relays individual to each of said trunk lines, and means controlled by each relay group for counting the number of impulses in each successive digit of the called telephone number. 115
- 55 21. In a telephone system wherein the digits of called telephone numbers are stored on storage sets common to a plurality of trunk lines, a group of counting relays upon which successive digits are temporarily stored, means for transferring the temporarily stored digit upon receipt thereof to one of said common storage sets, and means operated after the first digit for causing the busy tone to be transmitted to the calling subscriber in case all the storage sets are busy. 120
- 60 22. In a telephone system wherein the digits of called telephone numbers are stored on storage sets common to a plurality of trunk lines, a single-digit set of counting relays individual to each of said trunk lines arranged to respond successively to a plurality of digits in a called telephone number, and means for associating any counting relay set with any storage set in order to set said associated storage set. 125
- 65 23. In a telephone system, a trunk line terminating in a cord circuit, means for seizing said trunk line and for transmitting digits thereto, a storage set, means associated with said trunk line for connecting said trunk line with said storage set responsive to said seizure, and means whereby the first digit received on said trunk line after its seizure will be eventually stored in said storage set even though it is sent to said trunk line before the connection is made between the storage set and said trunk line. 130
- 70 24. In a telephone system, a line, a storage set for storing digits received over said line, means for associating said set with said line to store a digit received thereover, and means whereby said digit is eventually stored in said storage set even though it is received over said line before said storage set is associated therewith, said last means comprising 135

an all relay receiving device and means for transferring the digit from said device to said storage set.

25. In a telephone system, a digit receiving device comprising a plurality of relays, 5 a plurality of storage sets accessible to said device, means for associating an idle one of said storage sets with said device, means for successively registering a plurality of digits on said device, and means for transferring each of said digits from said device to the associated storage set as soon as received.

26. In a telephone system, a group of counting relays, storage sets each comprising a plurality of relay groups accessible to said counting relay group, means for associating an idle one of said storage sets with said counting relay group, means in the counting relay group for counting the number of impulses in each successive digit of a telephone number, and means for transferring each digit from the counting relay group to successive relay groups in the associated storage set as soon as received.

25 27. In a telephone system, a plurality of multi-digit storage sets on which telephone numbers are registered, means for selecting an idle storage set responsive to a call, and 30 means for preventing the mutilation of a digit due to its being dialed before the selection of a storage set, said means comprising a single digit receiving device comprising a group of counting relays on which the first digit may be registered while an idle storage set is being selected.

28. In a telephone system, a plurality of storage sets for storing the digits of a called telephone number, a number indicator controlled by said sets, automatic switching 40 means for selecting an idle storage set responsive to the initiation of a call, a digit receiving device wherein the first digit of a called telephone number may be temporarily stored until an idle storage set is selected, 45 and means for transferring the digit registered from the receiving device to the selected storage set prior to the receipt of the next digit of the called number.

50 29. In a telephone system, a digit receiving device effective immediately when taken into use for registering the first digit of a called telephone number, a plurality of storage sets, a number indicator controlled by 55 said sets, automatic switching means for selecting an idle one of said storage sets operated responsive to said receiving device being taken into use, and means for transferring the registered digit from the receiving device to the selected storage set prior to the receipt of the second digit of the called number.

30. In a telephone system, a digit receiving device, storage sets accessible to said device, means for associating an idle one of

said storage sets with said device, means for successively registering the digits of a called telephone number on said device, means for transferring the digits from said device to the associated storage set as soon as registered, 70 a plurality of signal lamps operable in various combinations under control of said storage sets, and means responsive when the last digit of the called telephone number has been transferred to the storage set for rendering said storage set effective to operate said signal lamps in a particular combination depending on the digits stored.

In witness whereof, I hereunto subscribe 80 my name this 29th day of March, A. D. 1927.

RUDOLPH FRANK STEHLIK.
